US0D1106669S

(12) United States Design Patent (10) Patent No.: US D1,106,669 S
Dooling (45) Date of Patent: * Dec. 23, 2025

(54) SELECTIVELY SEALABLE EVACUABLE STORAGE BAG

(71) Applicant: Load Lugger, LLC, Holly, MI (US)

(72) Inventor: Daniel J. Dooling, Fenton, MI (US)

(73) Assignee: Load Lugger LLC, Holly, MI (US)

() Term: 15 Years

(21) Appl. No.: 29/895,821

(22) Filed: Jun. 26, 2023

Related U.S. Application Data

(60) Division of application No. 29/768,661, filed on Jan. 31, 2021, now Pat. No. Des. 990,157, which is a continuation of application No. 29/685,563, filed on Mar. 29, 2019, now Pat. No. Des. 909,060.

CLAIM

The ornamental design for a selectively sealable evacuable storage bag, as shown and described.

DESCRIPTION

FIG. 1 is a top plan view of an embodiment of a selectively sealable evacuable storage bag; and,
FIG. 2 is a bottom plan view of the embodiment of FIG. 1. The broken line showing of the semi-automatic rifles forms no part of the claimed design.

1 Claim, 2 Drawing Sheets
